UNITED STATES PATENT OFFICE.

WILLIAM A. CONRAD, OF CHICAGO, ILLINOIS.

DESIGN FOR A SHAVING-OUTFIT HOLDER.

44,468.

Specification for Design.

Patented Aug. 12, 1913.

Application filed November 15, 1912. Serial No. 731,607. Term of patent 14 years.

To all whom it may concern:

Be it known that I, WILLIAM A. CONRAD, a citizen of the United States, and a resident of the city of Chicago, county of Cook, and State of Illinois, have invented a new, original, and ornamental Design for Shaving-Outfit Holders, of which the following is a specification, reference being had to the accompanying drawings, forming a part thereof.

Figure 1 is an elevation of a shaving outfit holder showing my new design, and Fig. 2 is a similar view of the same taken at substantially 90° on a horizontal plane from the view shown in Fig. 1.

I claim:

The ornamental design for a shaving outfit holder, as shown.

In testimony whereof I have signed my name to this specification in the presence of two subscribing witnesses.

WILLIAM A. CONRAD.
